UNITED STATES PATENT OFFICE.

DEWEY COOKE CANFIELD, OF EAST CANAAN, CONNECTICUT.

SHEET-METAL PRESS.

1,368,890.

Specification of Letters Patent. Patented Feb. 15, 1921.

Application filed April 6, 1920. Serial No. 371,616.

To all whom it may concern:

Be it known that I, DEWEY C. CANFIELD, a citizen of the United States, and resident of East Canaan, in the county of Litchfield 5 and State of Connecticut, have invented a new and Improved Sheet-Metal Press, of which the following is a full, clear, and exact description.

This invention relates to a sheet metal 10 press, and aims more particularly to provide a press adapted to form the ends of sheet metal drums, cans and receptacles in general, and for properly crimping the same.

It is well known that various machines 15 have been devised with a view of providing a press particularly adapted for use in connection with sheet metal receptacles, in which an expanding die is used for crimping or forming the end portions of the same. It 20 has further been proposed to utilize a contracting die for the same purpose.

Machines of this type have left much to be desired in that certain specific constructions have been employed for holding the 25 receptacles in place during the forming operation.

Where this crimping or retaining means was manually operated, a great amount of delay has been experienced. Where mechanically operated means has been utilized 30 for this purpose the construction devised to accomplish the result desired has added greatly to the cost of the machine. Without employing either manually or mechanically 35 operated retaining members in conjunction with a machine of this nature and relying solely upon gravity or the hands of the operator to hold the receptacle properly in position many defective articles have been produced. This is to be attributed to the fact 40 that the receptacles have not been properly held, resulting in a great waste of material and labor.

My invention now aims to provide a press 45 adapted for use in connection with sheet metal receptacles in which the receptacle will be firmly held in position and be operated upon to crimp or otherwise form the end of the same.

50 Reference is had to the attached sheets of drawings as illustrating one practical embodiment of my invention, and in which drawings,

Figure 1 is a sectional side view of my 55 press taken along line 1—1 of Fig. 2.

Fig. 2 is a plan view thereof, and

Fig. 3 is a sectional plan view taken along line 3—3 of Fig. 1.

In these views the reference numeral 5 indicates any suitable number of legs which 60 serve to support the table 6, which table is preferably circular in shape, as has been clearly shown in Fig. 2, and is adapted to receive that end of the container which is to be formed.

Now with a view of providing suitable means for crimping or forming the end of the container, a number of radially disposed die members 7 are slidably mounted upon the face of the table 6, such die members 70 having their working faces adjacent their inner ends.

A second die adapted to coöperate with the first named die members is also mounted upon the upper face of the table 6, such 75 second die conveniently including a number of wedge-shaped members 9 each formed adjacent their outer ends with a working face 10.

Each of these dies is formed with a shoulder 11 extending in an arc, such shoulders presenting an uninterrupted annular flange upon the die being properly assembled. Encircling this annular flange is a contracting 85 spring such as 12 serving to normally retain the dies in the position illustrated in Figs. 1 and 2.

It is now to be noted that the die formed by the plurality of members 7 presents in its projected position, indicated in dotted lines 90 in Fig. 2, an uninterrupted ring shaped working face.

With a view of properly holding and guiding the wedge-shaped members 9, headed lugs 13 have their inner ends secured 95 to the under faces of each of the wedge-shaped segments, such lugs extending through a plurality of radially disposed slots 14 formed in the table 6.

To now provide suitable operating and 100 timing mechanism serving to actuate the dies, I utilize in the embodiment shown a sliding shaft 15 projecting through the opening presented in the second die, formed by the wedge-shaped members 9, it being 105 noted that these members are formed in their lowermost portion of this opening with inclined faces adapted to coöperate with the beveled surface 16, forming a part of the shaft 15 for a purpose hereinafter more 110 fully described.

The outer ends of each of the die members

7 conveniently terminate in a pair of ears 17 between which extends a pin 18 serving to afford pivotal connection between these die members and levers 19 pivotally secured 5 subsequently intermediate their extremities to the table 6 as has been indicated by the reference numeral 20. The pivotal connection as has been clearly shown between the die members 7 and the levers 19 is provided 10 by the upper ends of such levers extending between the ears 17 adjacent which end these levers are formed with a transversely disposed oblong slot such as 21 through which slot the pin 18 extends.

15 A collar 22 is slidably keyed as at 23 upon the shaft 15, and this collar conveniently includes an annular groove or depression 24 into which extend the inner ends of connecting rods 25 the outer ends of which are pivotally secured as at 26 to the lower ends of the levers 19.

It will now be appreciated, that upon the collar 22 being moved longitudinally of the shaft 15 that the inner ends of the connecting rods 25 will be moved accordingly, the outer ends being projected outwardly, which action will be transmitted to the levers 19 serving to project the radially disposed dies 7 inwardly to the position indicated in dotted lines in Fig. 2. Further a movement bodily on the part of the shaft 15 will result in the wedge-shaped members 9 being projected outwardly to a position in which their working faces 10 are capable of co-operating with the working faces 8 of the die member 7.

With a view of accomplishing this result, and to properly time the same, a shaft 27 suitably mounted in bearings 28 upon the 40 supporting legs 5 is provided, which shaft receives its power from any suitable means such as a belt pulley 29 secured adjacent one of its ends. Its opposite end mounts a gear wheel such as 30 engaging a second gear 45 wheel 31, which latter gear serves to rotate the shaft 32. A third shaft 33 swingingly mounts a plurality of arms 34 which extend in pairs to each side of the shaft 15, and at a point below the collar 22. The opposite 50 ends of the arms 34 extend to a point above the shaft 32 which carries a plurality of fixed cams 35 corresponding in number to the arms 34 and lying directly below the free ends of the same.

55 It is now to be noted that the collar 22 is conveniently provided with a pair of lugs 36 extending outwardly therefrom at diametrically opposite points, and overlying the outermost arms 34. It will be seen that 60 upon the shaft 27 being rotated, and transmitting rotation to the shaft 32 that the cams carried by such shaft will serve to properly engage the innermost pair of arms 34, which engage with the pin 37 extending 65 transversely through the shaft 15, and that

upon a further rotation of the shaft 32, and consequential raising of the inner arms 34 that the shaft will be bodily moved upwardly, resulting in an outward projection of the wedge-shaped members 9 forming the 70 inner die.

It will be appreciated that this action will result in the holding of that end of the metallic receptacle to be formed, which receptacle, as has been indicated in Fig. 1 extends in that space normally existing between the working faces of the respective dies. Any possibility of the receptacle becoming displaced will have been eliminated by virtue of the fact that the working faces 80 10 now firmly engaging the inner surface of the receptacle, and upon a further rotation of the shaft 32 the outermost pair of arms 34 will be swung upwardly, and these arms upon engaging the lugs 36 of the collar 22 will serve to raise this member resulting 85 in an inward projection of the outer set of dies thus forming the upper end of the receptacle.

Having thus fully described my invention 90 what I desire to secure by Letters Patent is:

1. A press, including a table, a shaft extending through said table and presenting a beveled surface adjacent its point of penetration of the same, a die member including a plurality of wedge-shaped members slidably positioned upon said table, and having their inner ends bearing against said shaft, and being formed with an inclined surface adapted to co-operate with said beveled surface, a second die member including a plurality of radially disposed members slidably positioned upon said table, levers pivotally mounted upon said table and being pivotally secured adjacent their upper ends to 95 said radially disposed die members, connecting rods pivotally secured adjacent the lower ends of said levers, a slideable collar encircling said shaft, means tending to normally hold the first named die members in contracted position, lugs forming a part of said collar, a second shaft, cams mounted upon said second shaft, arms swingingly secured and having their free ends engaged by said cams, a transversely extending pin through the first named shaft, means for operating said cams, whereby to swing said arms to move said collar and operate the last named die member, and also to engage said first named shaft pin to expand the first named 100 die member.

2. A press, including a table formed with radially disposed slots, a die mounted upon said table, said die including a plurality of wedge-shaped members, means adapted to 115 co-operate with said members a shoulder formed upon each of the upper faces of said wedge-shaped members, and presenting in aggregate an annular flange, a spring encircling said flange for normally holding 120 125 130

said members in contracted position, means 5 for guiding the same upon said table, said means including a plurality of headed lugs projecting through the radially disposed slots in said table.

3. A press, including a table, a die positioned upon said table, a shaft extending through said table centrally of said die member, a second die member including 10 a plurality of radially disposed members slidably positioned upon said table, levers pivotally secured to said table and being pivotally secured adjacent their upper

ends to said radially disposed die members, connecting rods pivotally secured 15 adjacent the lower end of said levers, a slideable collar encircling said shaft, an annular groove formed in said collar adapted to receive the free ends of said connecting rods, a second shaft, cams mounted upon said 20 second shaft, and arms having their free ends engaged by said cams, whereby to swing said arms to move said collar and operate the last named die member.

DEWEY COOKE CANFIELD.
